UNITED STATES PATENT OFFICE.

CARL OSKAR RYDBERG, OF GOTTERBURG, SWEDEN.

PUMP.

Application filed September 10, 1924, Serial No. 736,849, and in Sweden March 31, 1924.

My invention relates to lubricators, and more specifically to an improvement in measuring sight feed lubricators. It is concerned with simplification to reduce the number of parts required and the amount of accurate machining necessary to make a satisfactory device, and to that end employs certain novel principles such as the use of a single pumping element to effect all the oil transference. Other features of importance include the localization of the moving parts and the use of a one-piece cam plate.

Further objects and advantages of the invention including a much more effective interchangeability of parts than obtained heretofore will become apparent as the description proceeds.

In the accompanying drawings:—

Figs. 1 and 2 are central vertical sections 20 of the lubricator at right angles to each other;

Fig. 3 is a horizontal section along the line 3—3 in Fig. 1;

Fig. 4 is a plan view of the top of the 25 lubricator;

Fig. 5 is a bottom plan view of the cam disc; and

Fig. 6 is a side view of the cam disc with 30 pump and associated parts.

In the embodiment of my invention selected for illustration, the lubricant container consists of casing 1, bottom 2 and top 4, the latter having a central cup 5 with perforated bottom and covered by a plug 6. An annular slide 7 rotates against the bottom 2, being pivoted on a central shaft 8 fastened to the bottom 2 and the top 4 at its ends. The shaft thus holds the parts in assembled relation. The slide 7 is unitary 40 with a worm wheel 10 driven by worm 11, the whole being axially slidable on shaft 8. Disc 10 and slide 7 are pressed downward against the bottom 2 by means of spring 9. Pump cylinder 12 is attached to disc 10 and 45 communicates with a hole 13 in the slide 7. Pump plunger 14 is provided with a properly formed head 14', which is kept in engagement with a cam disc 16 by means of a spring 15 in the bottom of the cylinder beneath the plunger.

A number of channels 17, 18, 19 and 24 in the bottom plate 2 are arranged in groups equal in number to the number of lubricating pipes for which the device is intended.

The orifices of said channels are arranged 55 in a circle as at 21, 22, 23 and 24, the radius of said circle being about equal to the distance from the center of the hole 13 to the center of the shaft 8, so that the pump cylinder can successively communicate with each 60 of said orifices 21—24 in each group. One of the channels, 24, in each group communicates with a lubricating pipe, attached to one of the spouts 3 beneath the bottom 2; the second, 17, with the oil container; the third 65 channel 18 with a pipe 25, which extends upwardly through the top 4 and is bent so that the oil can drop down from its mouth into a cup 27 formed in the top plate 4; and the fourth channel 19 opens into a pipe 26 ending in said cup 27. The pipes 25 and 26 70 form the visible passage for the oil and can of course be located anywhere outside the container 1.

The pump is operated by the cam disc in 75 the following manner: As hole 13 passes the orifice 21, the lubricant is sucked from the oil container. Then the plunger remains elevated until the hole 13 registers with the next orifice 22. At this moment 80 the plunger is lowered and expels the lubricant through the channel 12 into the pipe 25. After the orifice 22 has been passed, the plunger remains lowered until the next orifice 23 has been reached, when a new 85 suction movement takes place and oil from the pipe 26 is sucked in. After still another stationary period while passing from the orifice 23 to the orifice 24, the oil in the cylinder is forced out through the channel 24 90 into the lubricating pipe connected thereto. Thereafter, the same cycle is repeated beginning with the first orifice 21 of the second group. Thus the pump cooperates successively with all the orifices and all the 95 groups and continues its operations repeatedly.

Cam disc 16 is rigidly on shaft 8, and carries integral cams 28 at its circumference. The peripheral distance between the 100 centers of the cams 28 corresponds to the intervals between the pumping actions and is equal to the distance between the centers of the orifices 22 and 24. The tops of the cams are flat and the peripheral length of the 105 flat cam tops corresponds to the quiescent periods, or dwells of the plunger when lowered. The sides of the cams in peripheral

direction are preferably inclined at 45°. The dwells between the cams are flat, as at 31 and 32 and the peripheral length of these dwells corresponds to the quiescent periods of the plunger when elevated. Two pairs of inclined cam surfaces with cam tops and dwells therebetween cooperate with each group of orifices. The plunger head 14' has a wedge form with the edge somewhat rounded and with the sides of the wedge sloping at substantially the same angle as the sides of the cams.

In case more oil should be delivered through pipe 25 than is withdrawn through pipe 26, the cup 27 will overflow and oil will be lost. To eliminate this possibility, means are provided for adjusting the length of the plunger stroke so that it is less when the plunger sucks in oil from the container than when sucking oil from the pipe 26. For this purpose plate cam 33 or the like is provided, vertically slidable in a slot in the cam disc 16 through each dwell 31 so that the head of the plunger abuts 25 against said plate to limit its stroke. Each plate 33 is carried by a pin 34 sliding in an aperture in a disc 35 above the cam disc. Each pin 34 is provided with a flanged head 38 and a spring 36 tending to hold the head 30 against adjustment screw 37 threaded in the top 4, see Figs. 2 and 4. By means of screws 37 the plates 33 can be set in any desired vertical positions to limit the strokes of the plunger selectively. The slide 7 rotates in 35 the direction of the arrow in Fig. 3.

The top is provided with a cover 39 which is held in place by the threaded plug 6 and is made of glass or other transparent material in front of the cups 27 for observation 40 of the delivery of the oil.

A ball check valve may be inserted in the oil passage to the lubricating pipes as shown in the spouts 3 to prevent leakage of oil under slide 7 or lifting of the slide by 45 the back pressure of the oil.

It will be noted that the only precise surface fit required in the whole assembly, is that between slide 7 and the bottom plate on which it rides. The pivot for plate 10 50 need only be sufficiently accurate to secure substantial registry between orifice 13 and the openings over which it is to pass. Furthermore, the engagement between these surfaces being maintained by spring 9, no 55 temperature differences between the parts, with accompanying differences in thermal expansion, will interfere with maintaining perfect sliding contact between these surfaces.

60 Without further elaboration, the foregoing will so fully explain the gist of my invention, that others may, by applying current knowledge, readily adapt the same for use under various conditions of service, 65 without eliminating certain features which

may properly be said to constitute the essential items of novelty involved, which items are intended to be defined and secured to me by the following claims.

I claim:

1. In lubricators provided with a rotatable pumping device, the combination of a stationary bottom plate having a number of channels in it with their orifices arranged in a circle in groups of four, a slide rotatable around a shaft and covering said orifices, said slide being provided with one aperture so arranged that it communicates successively during the rotation with the orifices, a pump fixed to said slide above 75 said aperture, a cam disc fixed to said shaft and cooperating with the head of the pump plunger, one of said channels in each group communicating with the lubricators oil container, a second channel communicating with a pipe outside the oil container and bent at the end to allow its content to drop from its mouth, a third channel communicating with a pipe forming a cup at its end so located that it can receive the oil dripping from said mouth, a fourth channel 80 communicating with a lubricating pipe to the machine, means to rotate said slide with pump around said shaft, and said cam disc provided with cams at the circumference of 85 the disc in number equal to half the number of said orifices and so located in regard to said orifices that the pump will suck in the lubricant through the first and third orifices and discharge same through the second and 90 fourth orifices.

2. In lubricators provided with a rotatable pumping device the combination of a stationary bottom plate having a number of channels in it with their orifices arranged in a circle in groups of four, a slide rotatable around a shaft and covering said orifices, said slide being provided with one aperture so arranged that it communicates successively during the rotation with the orifices, a pump fixed to said slide above 105 said aperture, a cam disc fixed to said shaft and cooperating with the head of the pump plunger, one of said channels in each group communicating with the lubricators oil container, a second channel communicating with a pipe outside the oil container and bent at the end to allow its content to drip from its mouth, a third channel communicating with a pipe forming a cup at its end so located 110 that it can receive the oil dripping from said mouth, a fourth channel communicating with a lubricating pipe to the machine, means to rotate said slide with pump around said shaft, and said cam disc provided with cams at the circumference of the disc in 115 number equal to half the number of said orifices and so located in regard to said orifices that the pump will suck in the lubricant through the first and third orifices and 120 discharge same through the second and 125 fourth orifices.

5 discharge same through the second and fourth orifices, the cam disc with cams and gaps therebetween being provided with vertically adjustable plates in front of every second gap to control the length of the plunger stroke when sucking oil from the container.

10 3. In a device of the class described, in combination, an oil chamber, a sight chamber, a single pump, means for transferring measured charges from oil chamber to sight chamber by means of said pump, means for discharging measured charges from said sight chamber by means of said same pump, 15 and adjustment means for varying one charge independent of the other.

20 4. In a device of the class described, in combination, an oil chamber, a sight chamber, a pump comprising a single piston of uniform diameter, and a single cylinder receiving said piston, means for transferring measured charges from oil chamber to sight chamber by means of said pump, and means for discharging measured charges from 25 said sight chamber by means of said same pump.

30 5. In a circulator, in combination, a chamber, a flat plate mounted for rotation about the axis thereof, a single pump mechanism projecting axially from the periphery of said plate, said plate having an orifice opening into said mechanism, resilient means pressing said plate axially against the chamber wall to maintain a seal for said orifice, a plurality of sets of conduits debouching to register in succession with said orifice, each set including a supply conduit, a sight conduit, a return conduit or stand pipe, and a discharge conduit, said conduits registering with said orifice in the order named, 40 said sight conduit discharging visibly into said stand pipe, a first stationary cam plate spaced axially from said movable plate, inclined cam surfaces and dwells on said plate for controlling the movement of said pump mechanism to withdraw a measured charge from a supply conduit and deliver the same to a sight conduit and then to withdraw a charge from said stand pipe and force the same into said discharge conduit, a check valve in said discharge conduit, a plurality of bottom dwell cams controlling the amount measured, and individual means for adjusting the extent of each measuring stroke, said 50 bottom dwell cams and adjusting means comprising simple plates projecting through slots in said cam plate, vertical plungers carrying said dwell cams, a second cam plate carrying and guiding said plungers, springs urging said plungers up and adjusting screws threaded through the top of said chamber and bearing on the tops of said plungers.

60 6. In a circulator, in combination, a chamber, a flat plate mounted for rotation about

the axis thereof, pump mechanism carried by said plate, said plate having an orifice opening into said mechanism, resilient means pressing said plate axially against the chamber wall to maintain a seal for said orifice, 70 conduits debouching to register in succession with said orifice, a first stationary cam plate, inclined cam surfaces and dwells on said plate for controlling the movement of said pump mechanism, a plurality of bottom dwell cams controlling certain of the pump strokes, and individual means for adjusting the extent of said strokes, said bottom dwell cams and adjusting means comprising simple plates projecting through slots in said cam plate, 75 vertical plungers carrying said dwell cams, and a second cam plate carrying and guiding said plungers.

80 7. In a circulator, in combination, a chamber, a flat plate mounted for rotation about the axis thereof, pump mechanism carried by said plate, said plate having an orifice opening into said mechanism, resilient means pressing said plate axially against the chamber wall to maintain a seal for said orifice, 85 conduits debouching to register in succession with said orifice, a stationary cam plate, inclined cam surfaces and dwells on said plate for controlling the movement of said pump mechanism, a plurality of bottom dwell cams controlling certain of the pump strokes, and individual means for adjusting the extent of said strokes, said bottom dwell cams and adjusting means comprising simple plates projecting through slots in said cam plate, 90 vertical plungers carrying said dwell cams.

95 8. In a circulator, in combination, a chamber, a flat plate mounted for rotation about the axis thereof, pump mechanism carried by 100 said plate, said plate having an orifice opening into said mechanism, resilient means pressing said plate axially against the chamber wall to maintain a seal for said orifice, conduits debouching to register in succession with said orifice, a stationary cam plate, inclined cam surfaces and dwells on said plate for controlling the movement of said pump mechanism, a plurality of bottom dwell cams controlling certain of the pump strokes, 105 and individual means for adjusting said dwell cams.

110 9. In a circulator, in combination, a chamber, a flat plate mounted for rotation about the axis thereof, a single pump mechanism carried by said plate, said plate having an orifice opening into said mechanism, resilient means pressing said plate axially against the chamber wall to maintain a seal for said orifice, 115 conduits debouching to register in succession with said orifice, including a supply conduit, a sight conduit, a return conduit or stand pipe, and a discharge conduit, said conduits registering with said orifice in the order named, said sight conduit dis- 120

charging visibly into said stand pipe, and a stationary cam plate for controlling the movement of said pump mechanism to withdraw a charge from a supply conduit and 5 deliver the same to a sight conduit and then to withdraw a charge from said stand pipe and force the same into a discharge conduit.

10. In a circulator, in combination, a chamber, a movable member therein, a single pump carried by said member, conduits debouching to register in succession with said pump mechanism during movement of said member, including a supply conduit, a sight conduit, a return conduit or stand pipe, and 15 a discharge conduit, said conduits registering with said pump mechanism in the order named, said sight conduit discharging visibly into said stand pipe, a stationary cam plate, and inclined cam surfaces and dwells 20 on said plate for controlling the movement of said pump mechanism to withdraw a measured charge from a supply conduit and deliver the same to a sight conduit and then to withdraw a charge from said stand pipe and 25 force the same into said discharge conduit.

11. In a circulator, in combination, a chamber, a single pump mechanism movably mounted therein, conduits debouching to 30 register in succession with said mechanism including a supply conduit, a sight conduit, a return conduit or stand pipe, and a discharge conduit, said conduits registering with said mechanism in the order named, 35 said sight conduit discharging visibly into said stand pipe, and a stationary cam

plate for controlling the movement of said pump mechanism to withdraw a measured charge from a supply conduit and deliver the same to a sight conduit and then to withdraw a charge from said stand pipe and force the same into said discharge conduit. 40

12. In a circulator, in combination, a chamber, a flat plate mounted for rotation about the axis thereof, a single pump mechanism projecting axially from the periphery of said plate, said plate having an orifice opening into said mechanism, resilient means pressing said plate axially against the chamber wall to maintain a seal for said orifice, 45 conduits debouching to register in succession with said orifice including a supply conduit, a sight conduit, a return conduit or stand pipe, and a discharge conduit, said conduits registering with said orifice in the order 50 named, said sight conduit discharging visibly into said stand pipe, a stationary cam plate spaced axially from said movable plate, inclined cam surfaces and dwells on said plate for controlling the movement of said 55 pump mechanism to withdraw a measured charge from a supply conduit and deliver the same to a sight conduit and then to withdraw a charge from said stand pipe and force the same into said discharge conduit, a check 60 valve in said discharge conduit, a plurality of bottom dwell cams controlling the amount measured, and individual means for adjusting the extent of each measuring stroke. 65

In witness whereof, I hereunto subscribe my name this 21st day of August, 1924. 70

CARL OSKAR RYDBERG.
